MEAT-HOLDING MECHANISM FOR SLICING-MACHINES.

1,167,443.

Specification of Letters Patent.

Patented Jan. 11, 1916.

Application filed April 10, 1915. Serial No. 20,571.

To all whom it may concern:

Be it known that we, HOWARD STEPHENSON and JOSEPH LYONS HOWARD, of the city of Brantford, in the county of Brant, Province of Ontario, Canada, have invented certain new and useful Improvements in Meat-Holding Mechanism for Slicing-Machines, of which the following is a specification.

This invention relates to slicing machines in which a movable carriage is reciprocated parallel to a rotating knife, on which carriage the food to be sliced is supported and held on a laterally movable slide, and our object is to devise simple and effective mechanism for supporting the meat and for securely holding the ends of the pieces which have been sliced down too small to rest in a stable condition on the slide of the carriage.

We attain our object by providing a special gripping head which may be detachably supported on the slide, which head is provided with a plurality of arc-shaped gripping prongs which operate through holes in the head in reverse directions to grip the meat, substantially as hereinbefore more specifically described and illustrated in the accompanying drawings in which—

Figure 1 is a plan view of a slicing machine provided with our improved holding mechanism; Fig. 2 a front view of the holder and its supports; and Fig. 3 a vertical section of the holder.

In the drawings like numerals of reference indicate corresponding parts in the different figures.

Referring particularly to Fig. 1, 1 is the frame of the slicing machine provided with guides 2 on which the carriage 3 may be reciprocated parallel to the rotary knife 4. 5 is the fly wheel which is rotated by the operator. The connections from the fly wheel shaft whereby the carriage is reciprocated and knife rotated are not shown, as these form no part of the present invention. On the carriage 3 the slide 6 is transversely movable in the guides 7. The carriage supports the feed mechanism and the operating means therefor. These are shown but not described, as they form no part of this invention.

12 is a head formed as a casing. In the head 12 are journaled a plurality of parallel

transverse shafts 13, which are connected by gear wheels 14 so that alternate shafts may be given a rotary oscillating movement in opposite directions. Each shaft carries a series of gripping prongs 15, the upper ends of which are arc-shaped, the arcs being struck on circles having their centers in the axes of the shafts. By the movement of the shafts, these prongs may be thus projected through certain holes in the front of the head, their points subsequently recurving to reach or enter other holes formed in the front of the head. The holes, it will be seen on reference, particularly to Fig. 2, are arranged in pairs of rows, the holes of adjoining rows alternating with one another. We thus secure a series of gripping prongs operating in alternate rows in opposite directions, and these we find very effectively grip and hold the meat.

An important result follows from the arc-shaped arrangement of the gripping prongs, that is, the prongs at no time project away farther from the head than they do when moved to their limit to grip the meat. Thus there is no likelihood of the knife hitting the prongs if the user has inadvertently failed to move the prongs to their limit when engaging them with a piece of meat as sometimes happens with some of the older constructions.

The head is provided with a handle 16 and extended lugs 17 provided with elongated slots 18 adapted to pass over the ratchet rack bars 19, which at their lower ends are pivoted on the slide by means of the bolts 20. By means of these rack bars, the head 12 may be supported in any desired position above the slide. It may be disengaged any time by rocking the rack bars so that they disengage from the ends of the slots. It will be noted that one of the shafts 13 is provided with a handle 21 by means of which it may be rocked through the medium of the gear wheels 14 simultaneously operating the other shafts.

What we claim as our invention is:—

A meat holder for slicing machines comprising a head having a plurality of rows of holes formed in its face arranged in pairs; a plurality of shafts journaled in said head; intermeshing gears on each shaft whereby

the shafts may be alternately oscillated in opposite directions; gripping prongs secured to said shafts having arc-shaped outer ends adapted to be protruded from the holes of one row of each pair and to enter the holes of the other row of each pair.

Signed at Toronto this 2nd day of March

1915, in the presence of the two undersigned witnesses.

HOWARD STEPHENSON.
JOSEPH L. HOWARD.
